UNITED STATES PATENT OFFICE.

FREDERICK G. FARR, OF DETROIT, MICHIGAN, ASSIGNOR TO E. B. CADWELL & COMPANY, OF DETROIT, MICHIGAN, A COPARTNERSHIP.

FUEL-SUPPLY TANK.

1,065,435.

Specification of Letters Patent. Patented June 24, 1913.

Application filed July 15, 1909. Serial No. 507,863.

To all whom it may concern:

Be it known that I, FREDERICK G. FARR, a citizen of the United States, and resident of Detroit, in the county of Wayne and State 5 of Michigan, have invented certain new and useful Improvements in Fuel-Supply Tanks, of which the following is a specification.

This invention relates to improvements in oil storage and distribution systems for 10 boats.

The objects which the present invention has in view are: to provide a system for feeding oil from a storage tank under a constantly equal head: to provide a system 15 wherein the pressure for feeding oil to the engine is automatically controlled: to provide means for automatically receiving oil into the storage tank while maintaining the oil feed pressure: to provide a storage tank 20 for liquids wherein there is provision made for avoiding the surging of the liquids.

One embodiment of the present invention is shown in the accompanying drawing, which is a diagrammatic view of the invention, 25 showing the same as installed in a boat.

The view shows a forward section of the interior of the boat.

The invention is particularly designed for 30 the equipment of motor boats wherein gasoline is carried. The storage tank for the gasoline is usually placed in the bow of the boat while the engine is preferably disposed in the stern, or midships of the boat. 35 The engine is connected to the tank by the pipes —3—4— the former being the gasoline feed for the carburetor while the pipe —4— is for the delivery of water to the storage tank, this water being pumped by 40 the engine either as a part of the water circulating system of the engine or as an adjunct thereto. If the pump is a part of the circulatory system of the engine, suitable provision must be made for cooling the wa- 45 ter before introduction into the tank —5.

The gasoline —6— in this invention is contained in the tank —5— and is supported therein by the water —7— which is introduced below the gasoline, preferably into 50 an extension or leg —8. It will be understood that the gasoline contained in the tank —5— is delivered therefrom by water being introduced into the tank and displacing upward the said gasoline.

The relation between gasoline and water 55 in their specific gravity is that of 17 to 12. In other words, a column of water 12 inches high will support a column of gasoline 17 inches high. In the present invention this fact is utilized in that we have provided a 60 constant waterhead which is in the present situation the top of the chamber —9— into which the supply pipe —4— delivers the water and from which is extended an over- 65 flow pipe —10— that leads to the outside 70 and discharges the surplus water beyond the side of the boat. The chamber —9— is provided with a pipe —11— which extends in to the bottom of the leg —8— of the tank —5— and constituting the water-inlet there- 75 for. In the introduction of water, it is carried through the pipe —4— into the chamber —9— and from thence into the bottom of the leg —8— and then it is carried upward through the said leg to spread over the bottom of the tank —5— to support the gaso- 80 lene —6— contained therein.

The column of water extending from the bottom of the tank —5— to the top of the chamber —9— will support a column of 80 gasoline of the same height plus five-twelfths of the water column. The same column of water will of course support a column of water of the same height. Therefore a column of water and gasoline mixed 85 will be supported by the same water column to a height in excess of the column of water, proportional to the mixture. In other words, the head of the water column will be constant, while the head of the gasoline column will be constantly lessening as the proportion of gasoline in that column diminishes. Within this range of diminution of the head of the gasoline columns there is introduced a sight gage —12. 90 95

The enlarged pipe section —13— which is extended from the top of the tank —5— is in open communication therewith. From the section —13— is extended a smaller filling pipe —14— provided at the upper 100 end with a funnel —15. From the pipe —14— and just above the top of the section —13— is extended the oil delivery pipe —3— which leads to the carburetor for the engine. The gage 12 is preferably connected to the pipe 14 at a point above the pipe 3. By this arrangement when the gage indicates that the gasoline has been 105

exhausted there will still be a supply in the tank which tends to prevent the tank from being drained of gasoline.

The section —13— serves as a separating chamber to permit any water which may be held in suspension in the gasoline to settle and separate from the gasoline before entering the pipe —14. The pipe —14— being of small diameter as compared with the section —13— it operates to retard the upward movement of the gasoline contained in the section —13. This retardation permits the water to separate out. It is to prevent any agitation of the gasoline contained in the section —13— which might arise from surging of the gasoline contained in the tank —5— that I have provided the flared extension —16— which is shaped somewhat after the form of an inverted frusto conical section. In operation should the material in the tank —5— surge, this extension would deflect the material downward from the opening of section —13. Mounted within the inverted frusto conical member 16 is a deflector 17, preferably cone shaped, which is supported from the member 16 by arms 18. The purpose here is that during the operation of filling, the gasoline is caused to spread and is prevented from boring.

The operation of a device of the character described is as follows: The supply to the carburetor being closed, gasoline is poured into the funnel —15. As described, the column of water of a height to the overflow —10— will sustain a column of gasoline only, to the top of the gage —12. Therefore as the gasoline is now poured into the funnel —15— and pipe —14— the column of gasoline and water represented by the tank —5— section —13— and pipe —14— becomes heavier than the column of water contained in the pipe —11— and therefore the water contained therein is forced out of the overflow —10. This continues as the gasoline is poured in, until the tank —5— section —13— and pipe —14— becomes filled entirely with gasoline when it will be found that the balance between the gasoline column and the water column has been reached and the gage —12— will show the head of the gasoline at the top of the said gage. As the engine is operated, the gasoline is consumed, but the hydrostatic pressure on the gasoline is sufficient to maintain the level of the gasoline within the pipe 14 above the point of communication of the pipe 3 therewith until the tank is practically emptied of gasoline. The water circulation system is continuously operated by the engine to deliver water into the chamber —9. If the said chamber is filled, the surplus is delivered from the overflow —10— beyond the outside of the boat. If the chamber —9— has become in

any way exhausted by the decline of the water contained therein, due to the lessening of the balancing gasoline column, then the water circulation immediately replaces the exhaust to maintain the water column constant. This operation is automatic and continuous. The water is constantly displacing and replacing the gasoline, as the same is being consumed. As the gasoline is consumed, however, it will be noticed that the gasoline column is becoming gradually more largely water and the combined water and gasoline column is more nearly approaching the water column. This results in a gradual diminishing index on the gage —12.

What I claim as my invention is:

1. The combination with a tank, of a water inlet connection for the tank communicating therewith adjacent its bottom, a separating chamber located on the top of the tank and provided with an inverted frusto conical wall at the lower end of said chamber, and an oil delivery pipe communicating with said separating chamber.

2. The combination with an oil storage tank, of a water separating chamber located on the top of the tank and provided with an inverted frusto conical wall having an opening therein, and a cone-shaped deflecting device disposed within said wall above said opening.

3. The combination with a tank, of a water chamber, means permitting the overflow from said chamber whereby a constant head of water is maintained therein, a water inlet pipe for the tank leading from said chamber to adjacent the bottom of the tank, a separating chamber at the top of the tank and in proximity to the water chamber, and an oil delivery pipe communicating with the separating chamber at a point above the overflow means.

4. The combination with a storage tank, of a water chamber mounted on the top of the tank, a water supply connection for the chamber, an overflow connection for said chamber whereby a constant head of water is maintained therein, a water inlet connection for the tank leading from said chamber to adjacent the bottom of the tank, a separating chamber on the top of the tank, and an oil delivery conduit communicating with said separating chamber at a point above the water overflow.

5. The combination with a storage tank, of a closed water chamber, an inlet connection for continuously supplying said chamber with water, a water overflow connection for the chamber whereby a constant head of water is maintained therein, a water inlet connection for the tank leading from said chamber to adjacent the bottom of the tank, a separating chamber extending above the tank, and an oil delivery pipe leading from

said separating chamber and communicating therewith at a point above the water overflow.

6. The combination with a tank, of a water chamber mounted on the top of the tank, a supply connection for the chamber leading from a source at a distance from the tank, a water inlet connection for the tank leading from said chamber to adjacent the bottom of the tank, a separating chamber, and an oil delivery pipe communicating with the separating chamber at a point above the water overflow.

7. The combination with a tank, of a water separating chamber communicating with said tank and having the lower end

thereof provided with an inverted frusto conical wall having an opening therein, a cone-shaped deflector disposed within said wall above said opening, an oil supply pipe 20 for the tank, an oil delivery pipe communicating with said supply pipe, and a gage mounted on said supply pipe above the oil delivery pipe.

Signed at Detroit in the county of Wayne 25 and State of Michigan this 12th day of July A. D. 1909.
